UNITED STATES PATENT OFFICE.

HUBERT OSWALD BEDGOOD, OF GLASGOW, SCOTLAND, ASSIGNOR TO LOBNITZ & COMPANY LIMITED, OF RENFREW, SCOTLAND.

GUIDE OR FAIR-LEAD FOR THE DRAG ROPE OF A DRAG-LINE EXCAVATOR.

Application filed May 6, 1924. Serial No. 711,483.

To all whom it may concern:

Be it known that I, HUBERT OSWALD BEDGOOD, of Glasgow, Scotland, a subject of the King of Great Britain, have invented a certain new and useful Improved Guide or Fair-Lead for the Drag Rope of a Drag-Line Excavator, of which the following is a specification.

This invention, which relates to drag-line excavators, has for its object to improve and simplify the construction of the guide or fair-lead for the drag-line.

At present, in drag-line excavators, it is usual to employ a heavy cast steel fair-lead in which the vertical guide pulleys are carried but, under this invention, the fair-lead comprises forged steel hinge pieces to which steel plates are secured, the hinge pieces being pivotally secured to forge steel brackets bolted to the structure of the excavator, the whole constituting an improved construction or arrangement and combination of parts.

The improved fair-lead is shown on the accompanying drawings, whereon:—

Fig. 1 is an elevation with part in section, and

Fig. 2 a plan view taken along the section line A—A of Fig. 1.

The fair-lead comprises two bifurcated hinge pieces, 1, 1, of forged steel upon whose inner faces two parallel steel plates 2, 2, of the shape shown in Fig. 1 are riveted, the ends of the hinge pieces 1, 1 being enlarged to allow of holes being drilled therein and through the plates to provide bearings for spindles 3, 3 on which two sheaves 4, 4^a of cast steel are rotatably mounted, the lower sheave 4^a being of larger diameter than the upper 4. The spindles 3, 3, are each secured by a nut and split pin. This portion of the device is attached to the platform 5 by means of two forged steel brackets 6, 6, one secured to the upper edge and the other to the lower edge of the said platform. A hole is drilled in each bracket to correspond with a hole in the inner extremity of the corresponding hinge piece 1 aforementioned. Each hinge piece is secured to its bracket by a heavy pin 7 passing through the holes, and retained in place by a nut and split pin. In this way this portion of the fair-lead is pivotally mounted on the platform 5 with its sheaves 4 and 4^a in a vertical plane, the connecting pins

being held rigid with the brackets 7 by means of feathers.

In conjunction with the fair-lead is a guide mounted in the platform 5 and comprising a rectangular slot 8 cut in the end of the platform, along the upper and lower edges respectively of which two channel bars 9 and 9^a are riveted by one flange of each, to the end of the platform, flush with the edges of the slot. By giving these flanges a slight set the webs of the bars are inclined at a small angle to the horizontal and are parallel. These two channel bars 9 and 9^a are drilled to provide bearings for two spindles 10, 10 upon which two sheaves 11, 11 of equal size are rotatably mounted in a plane parallel to that of the webs of the bars 9, 9^a, the spindles being secured in place by the usual nuts and split pins. As will be seen from Fig. 2 the sheaves 11, 11 are symmetrically disposed with reference to the brackets 6, 6 on which the fair-lead is mounted, sufficient space being allowed between them for the passage of the drag-line 12.

For the efficient lubrication of the parts, the bearing spindle of each sheave 11, 11, has an axial hole 13 drilled in it for about half its length, this hole connecting, at its inner end, with a hole 14 drilled radially and opening on to the bushing of the sheave 11, the other end of the axial hole 13 being connected to a small tube 15. Heavy lubricant is forced along the tube 15 to the axial hole 13 whence it passes by the radial hole 14 to the bearing.

The action of the fair-lead is evident from the drawings. The drag-line 12 from the bucket passes in between the two vertical sheaves 4 and 4^a in an approximately horizontal direction, then through the slot 8 in the platform 5 and between the two horizontally arranged but slightly inclined sheaves 11, 11 to the drag drum of the winding engine. In order to minimize the risk of the line chafing on the side plates 2, 2, as it enters the fair-lead the front edges of the said plates are given an outward set at 16.

Having now fully described my invention what I claim and desire to secure by Letters Patent is:—

1. A fair-lead for the drag-line of a drag line excavator, having, in combination with the hollow platform of the excavator horizontally disposed guide pulleys located

- within said platform, said platform having an opening therein through which the drag-line passes, means supporting the guide pulleys horizontally side by side within the 5 platform, brackets projecting from the platform, bifurcated hinge pieces pivotally connected to said brackets, and vertically disposed pulleys mounted on the bifurcated hinge pieces.
- 10 2. A fair-lead for the drag-line of a drag-line excavator, having, in combination with the hollow platform of the excavator, oppositely disposed channel bars secured within the platform of the excavator, guide pulleys mounted between the channel bars at an angle slightly inclined to the horizontal, and partially projecting through said platform, bifurcated hinge pieces pivotally connected to the platform, and vertically disposed pulleys pivoted to the hinge pieces within the bifurcations thereof.
- 15 3. A fair-lead for the drag-line of a drag-line excavator, having in combination with the hollow platform of the excavator, oppositely disposed channel bars secured within the platform, guide pulleys mounted between the channel bars at an angle slightly inclined to the horizontal, forged steel brackets on the platform, bifurcated hinge pieces 20 pivotally connected to said brackets, a plate secured to both the bifurcated hinge pieces on one side, and a similar plate secured to both the bifurcated hinge pieces on the other side whereby both hinge pieces will be caused to swing together, and vertically disposed pulleys pivoted to the hinge pieces between said plates.
- 25 30

on one side and a similar plate secured to both the bifurcated hinge pieces on the other side whereby both hinge pieces will be caused to swing together, and vertically disposed 35 pulleys pivoted to the hinge pieces between said plates.

4. A fair-lead for the drag-line of a drag-line excavator, having in combination with the hollow platform of the excavator, oppositely disposed channel bars secured within the platform, two guide pulleys mounted between the channel bars at an angle slightly inclined to the horizontal, two pivot pins, one for each guide pulley, the pins being 40 carried by the channel bars, means for lubricating the pulleys through said pins, forged steel brackets on the platform, bifurcated hinge pieces pivotally connected to said brackets, a plate secured to both the 45 bifurcated hinge pieces on one side, and a similar plate secured to both the bifurcated hinge pieces on the other side whereby both hinge pieces will be caused to swing together, and vertically disposed pulleys pivoted to the hinge pieces between said plates. 50

In testimony whereof I affix my signature in presence of two witnesses.

HUBERT OSWALD BEDGOOD.
